UNITED STATES PATENT OFFICE.

JOHN SCHUTZ, OF NEW YORK, N. Y.

STOP MOTION FOR KNITTING MACHINES.

1,414,218.

Specification of Letters Patent. Patented Apr. 25, 1922.

Application filed July 8, 1920. Serial No. 394,723.

To all whom it may concern:

Be it known that I, JOHN SCHUTZ, a citizen of the United States, and a resident of the city of New York, borough of the Bronx, 5 in the county of Bronx and State of New York, have invented a new and Improved Stop Motion for Knitting Machines, of which the following is a full, clear, and exact description.

10 The invention is an improvement on the stop motion shown in the application filed by me July 5, 1919, Serial No. 308,877.

The object of the invention is to provide a new and improved stop motion for knitting machines of the reciprocating carriage type and arranged to automatically stop the machine on the yarn running out or in case the yarn breaks or a knot is in the yarn.

Another object is to render the stop motion exceedingly sensitive and to allow adjustment thereof according to the strength of the yarn used at the time.

Another object is to maintain a uniform tension on the yarn throughout the stroke 25 of the carriage especially when knitting tapering goods such, for instance, as sleeves which gradually narrow down beginning at the upper end.

Another object is to provide a long length 30 of the yarn to render the stop motion exceedingly useful on a Lamb machine having a long sweep.

With these and other objects in view, the invention consists of certain novel features 35 of construction as hereinafter shown and described and then specifically pointed out in the claims.

A practical embodiment of the invention is represented in the accompanying drawings forming a part of this specification, in which similar characters of reference indicate corresponding parts in all the views.

Figure 1 is a side elevation of the improved stop motion;

45 Figure 2 is an enlarged plan view of the same;

Figure 3 is an enlarged cross section of the same on the line 3—3 of Figure 1;

Figure 4 is a sectional side elevation of 50 part of the same on the line 4—4 of Figure 3;

Figure 5 is an enlarged side elevation partly in section of the improved stop motion and with the parts in normal working position and showing in dotted lines the 55 position of the parts on breaking the yarn;

Figure 6 is a side elevation of a portion

of the stop motion with the parts in position when a knot in the yarn actuates the stop motion;

Figure 7 is a side elevation of the stop motion with the parts in released position caused by the yarn being wound too tightly on the bobbin; 60

Figure 8 is a similar view of the stop motion with the parts in position when the yarn 65 runs out;

Figure 9 is an end elevation of the same; and

Figure 10 is a rear view of the same.

The improved stop motion presently described in detail is more especially designed for use on a straight knitting machine provided with suitable stopping means (not shown) for stopping the machine. The stopping means for an actuating member 70 such as a shipper lever or the like is connected by a chain, cable or other flexible connection 20 with a ring 21 held on the lower end of a slide 22 mounted to slide up and down in a casing 23 attached to a stand 80 24 mounted on top of the knitting machine adjacent one end thereof. The slide 22 is pulled upward by a pull spring 25 secured at its lower end on a pin 26 attached to the slide 22 and fastened at its upper end by a 85 screw 27 to the casing 23 at the top thereof. The pin 26 engages the notched locking heel 30 of a lever 31 fulcrumed at its lower end at 32 within the casing 23. The upper end of the lever 31 is adapted to be engaged by 90 the end 33 of a releasing lever 34 fulcrumed at 35 within the casing 23 and extending through a slot 35^a formed in the top of the said casing 23. It will be noticed that when the slide 22 is in set or lowermost position, 95 as shown in Figures 1 and 5, then the spring 25 is held under tension with the pin 26 engaging the notched locking heel 30 to hold the lever 31 in engagement with the tripping end 33 of the releasing lever 34. It will be 100 noticed that when the releasing lever 34 is given a swinging motion from the right to the left (see dotted lines in Figure 5) then the tripping end 33 moves out of engagement with the upper free end of the lever 31 and 105 disengages the pin 26 to allow the spring 25 to quickly pull the slide 22 upward thus actuating the stopping means of the knitting machine to stop the latter. It will be noticed that the locking and releasing devices 110 for the slide 22 are very sensitive and a slight movement given to the releasing lever

34 from the right to the left releases the lever 31 whereby spring 25 is released and the slide 22 moves quickly into uppermost stopping position.

- 5 The releasing lever 34 is adapted to be engaged by an arm 40 adjustably secured by a set screw 41 to a rock shaft 42 journaled in suitable bearings 43 and 44 arranged on the stand 24. On the rock shaft 42 is adjustably secured an arm 45 by the use of a set screw 46 and this arm 45 is connected by a cord or other flexible connection 47 with the lower end of an arm 48 adjustably secured at its upper end by a set screw 49 to a transverse shaft 50 which is journaled in a bushing 51 attached by a set screw 52 to a bearing 53 arranged on a horizontal arm 54 of the stand 24. On the rear end of the shaft 50 is secured or formed an upwardly extending arm 55 terminating in an angular lug 56 extending into the path of a sweep rod 60, preferably of spring wire, and formed into an eye 61 engaging a screw 62 screwing in a flange 63 formed on a hub 64 mounted to turn loosely on the bushing 51 (see Figure 3). The sweep rod 60 terminates in an arm 65 (see Figure 4) engaged by one end of a spring 66 extending around the hub 64 and connected at its other end to a set screw 67 screwing in a collar 68 adjustably mounted on a rod 69 attached to the rear end of the arm 54. The set screw 67 serves to fasten the collar 68 in position on the rod 69, after the collar 68 is adjusted, to give the desired tension to the spring 66.

The outer or free end of the sweep rod 60 supports a yarn guide 70 of porcelain or other suitable material, and through which 40 the yarn 71 passes, also passing through an eye 72 formed in the outer end of the arm 54. The yarn after leaving the eye 72 passes through the usual yarn guide (not shown) on the carriage of the knitting machine. The yarn prior to reaching the yarn guide 70 passes through an eye 73 arranged on the arm 54 in the rear of the eye 72. It will be noticed that by the arrangement described the sweep rod 60 is held 45 under tension during the time the knitting machine is running, and the sweep rod 60 is of considerable length to allow free up and down swinging of the sweep rod according to the pull exerted by the carriage 50 on the yarn 71. In case the yarn breaks, the sweep rod 60 is released and swings upward and in doing so strikes the lug 56 thus imparting a rearward swinging movement to the arm 55 of the shaft 50 whereby 55 the latter is turned. This turning movement of the shaft 50 causes the arm 48 to swing forwardly and upwardly as indicated in dotted lines in Figure 5, whereby the flexible connection 47 is drawn taut and 60 finally exerts a pull on the arm 45 and

swings the same (see dotted lines in Figure 5) whereby the shaft 42 is correspondingly turned and its arm 40 actuates the releasing lever 34 to swing the latter in released position relative to the lever 31. 70 When this takes place the slide 22 and the stop mechanism of the machine are actuated to stop the machine.

In order to actuate the lever 34 for releasing the slide 22 in case the yarn 71 is 75 provided with a knot 75 (see Figure 6), the following arrangement is made: On the arm 48 previously mentioned is secured a pin 80 adapted to be engaged by an arm 81 mounted to swing on a pivot 82 held on a bracket 83 forming part of the arm 54 and the stand 24. On the arm 81 is secured a jaw 84 by the use of a screw 85 and this jaw 84 overlies the arm 81 and forms with the same a passage for the yarn 71 (see Figure 3). The passage can be increased or diminished in width by a set screw 86 screwing in the arm 81 and having its head engaging the jaw 84. The passage is sufficiently narrow to prevent a knot 75 in the 90 yarn 71 from passing through the passage and hence when the knot reaches the passage it abuts against the right-hand edges of the arm 81 and the jaw 84 whereby the pull on the yarn causes the arm 81 to swing from 95 the right to the left and in doing so it imparts a swinging motion to the arm 48 by the pin 80. This swinging movement given to the arm 48 draws the flexible connection 47 taut, the same as above described relating to the breaking of the yarn, and finally the shaft 42 is rocked and the lever 34 is actuated by the arm 40 to release the slide 22 to cause the machine to stop. The arm 81 normally rests on a stop pin 87 arranged 105 on the bracket 83, as plainly shown in Figure 5, and the yarn passes freely between the arm 81 and its jaw 84 until a knot 75 imparts a swinging motion to the arm 81, as above explained. In order to properly 110 guide the yarn 71 through the passage formed by the arm 81 and its jaw 84 use is made of a guide roller 90 and an eye 91, of which the guide roller 90 is journaled on the bracket 83 above the shaft 42, and the 115 eye 91 is formed in the arm 54, as plainly indicated in Figure 5.

In order to stop the machine in case the 120 yarn 71 is wound too tightly on its bobbin 95, the following arrangement is made, special reference being had to Figures 5 and 7: The yarn prior to reaching the guide roller 90 passes around a guide 100, preferably made of porcelain, and attached to the upper end of a lever 101 fulcrumed at 125 102 on a bracket 103 forming part of the arm 54 of the stand 24. A spring 104 is connected at one end with a lever 101 and at the other end to the bracket 103 to normally hold the lever 101 in an approxi- 130

mately vertical position (see Figures 5, 6, 8 and 10) and against a stop pin 105 held on the bracket 103. The lower end of the lever 101 is provided with an angular arm 5 101^a adapted to engage the arm 45 on the rock shaft 42 to rock the latter on swinging the lever 101 from the left to the right (see Figure 7) in case the tension of the yarn is increased on account of binding on the 10 bobbin 95, through tight winding thereof.

In order to actuate the stopping mechanism in case the yarn runs out the following arrangement is made: The yarn after leaving the bobbin 95 passes through an eye 15 110 (see Figure 5) formed on the bracket 103. The yarn then passes around a guide 111 and then between two disks 112 and 113 forming part of a tension device for the yarn. The disks 112 and 113 are mounted 20 on a rod 114 attached to the bracket 103, and the disk 113 is pressed towards the disk 112 by a spring 115 coiled on the rod 114 and abutting against a nut 116 screwing on the rod 114 to permit of adjusting the tension 25 of the spring 115. A jam nut 117 screwing on the outer end of the rod 114 serves to lock the adjusted nut 116 in the adjusted position. The yarn after passing between the tensioning disks 112 and 113 30 passes between two guide rods 120 and 121, of which the guide rod 120 forms part of the rod 121 attached to the rod 114 and also carrying the guide rod 111 previously mentioned. The rod 121 normally extends 35 above the rod 120 and forms part of an arm 125 provided with a weight 126 fulcrumed at 127 on the bracket 103. The weight 126 extends into the path of a lug 130 formed on an arm 131 secured by a set screw 132 to the rear end of the shaft 42, as plainly 40 shown in Figure 10. Normally the weight 126 is in uppermost position, as indicated in Figure 7, that is, a distance away from the angular lug 130. By reference to Figures 1, 5, 6 and 7 it will be noticed that the 45 tension of the yarn between the tensioning disks 112 and 113 and the guide 100 holds the rod 121 in uppermost position and likewise the weight 126. Now in case the yarn 50 runs out on the bobbin 95 and finally passes out between the tensioning disks 112, 113 then it releases the rod 121, and the weight 126 thereof now swings downward and in doing so strikes the lug 130 (see Figures 55 8, 9 and 10) thus imparting a downward swinging movement to the arm 131. When this takes place a rocking motion is given to the rock shaft 42 whereby the arm 40 imparts a swinging motion to the releasing 60 lever 34 to release the lever 31 and consequently the slide 22 to stop the machine, as previously explained.

When the yarn breaks at the front the rod 60 acts to stop the machine quickly, but in 65 event of its running out or breaking at the

rear it would take so long for the yarn to act on the rod 60 that the machine would not be stopped quickly, and it is to enable the machine to be stopped quickly whenever the yarn runs out or breaks at the rear that I 70 have devised the stop motion shown in Figures 8, 9 and 10.

From the foregoing it will be seen that by the arrangement described the knitting machine is stopped automatically and quickly in 75 case the yarn breaks at any point between the bobbin and the carriage of the knitting machine, or in case a knot in the yarn engages the arm 81 and its jaw 84, or in case the yarn is wound too tightly on its bobbin 80 95, or the yarn runs out.

It will further be noticed that the mechanism is exceedingly sensitive and is not liable to get easily out of order. By the use of the long sweep rod 60 and the devices 85 connected therewith a uniform tension is had on the yarn throughout the stroke of the carriage thus facilitating, particularly, knitting of tapering goods, such, for instance, as sleeves which gradually narrow down beginning at the upper end.

Having thus described my invention, I claim as new and desire to secure Letters Patent:—

1. In a stop motion for knitting machines, 95 an actuating mechanism for the stopping mechanism of the machine provided with a releasing device, a rock shaft having arms of which one is adapted to engage the said releasing device, and a spring-pressed upright lever provided at one end with a guide for the passage of the yarn from the bobbin to the knitting needles, the other end of the said lever extending downwardly at one side of the rock shaft and adapted to engage another arm of the rock shaft on excessive tension of the yarn on the bobbin to rock said shaft and cause the first arm to operate the releasing device.

2. In a stop motion for knitting machines, 110 an actuating mechanism for the stopping mechanism of the machine provided with a releasing device, a rock shaft having arms of which one is adapted to engage the said releasing device, a tension device for the passage 115 of the yarn, a pair of arms between which passes the yarn adjacent the said tension device, one of the said arms being fixed and the other being mounted to swing, and a weight on the swing arm and adapted to engage another of the said arms on the rock shaft.

3. In a stop motion for knitting machines, 125 a releasing device for the stop mechanism of the machine, a rock shaft having a plurality of arms, one of which is adapted to engage the releasing device to release the same, and a pivoted and spring pressed upright lever, said lever being pivoted intermediate of its ends to form members of unequal length, the 130

longer member having a guide for the passage of the yarn and its shorter member extending downwardly at one side of the rock shaft and having an angular end adapted to engage another arm of the rock shaft to rock said shaft and thereby cause the first arm to operate the releasing device.

4. In a stop motion for knitting machines, a releasing device for the stop mechanism of the machine, a rock shaft having a plurality of arms, one of which is adapted to engage the releasing device to release the same, a tension device for the passage of the yarn, a pair of arms between which passes the yarn adjacent the tension device, one of the arms being fixed and provided with a guide rod and the other pivotally mounted and provided with a weight adapted to engage an-

other arm of the rock shaft to operate said shaft and cause the first named arm to operate the releasing device. 20

5. In a stop motion for knitting machines, a releasing device for the stop mechanism of the machine, a rock shaft having a plurality of arms, one of which is adapted to engage 25 the releasing device to release the same, a tension device for the yarn, two guide arms between which the yarn passes, one of which is pivoted and a weight fulcrumed on a fixed support and mounted on an arm carried by the pivoted guide arm, said weight being adapted to engage an arm of the rock shaft to rock said shaft and cause the first named arm to operate the releasing device. 30

JOHN SCHUTZ.
